UNITED STATES PATENT OFFICE.

JOHN C. B. WOOD, OF HUNTINGTON, WEST VIRGINIA.

STRAIN-APPLYING APPARATUS.

1,127,341.

Specification of Letters Patent.

Patented Feb. 2, 1915.

Application filed October 20, 1913. Serial No. 796,319.

To all whom it may concern:

Be it known that I, JOHN C. B. Wood, citizen of the United States, residing at Huntington, in the county of Cabell and State of West Virginia, have invented certain new and useful Improvements in Strain-Applying Apparatus, of which the following is a specification.

This invention relates to improvements in devices for applying strain to members or structures, more particularly to the strand wires of fences, but which may be applied to other purposes without material structural change, and has for one of its objects 10 to improve the construction and increase the efficiency and utility of devices of this character.

Another object of the invention is to provide a simply constructed device of this 20 character which may be actuated from either side or both sides at the same time.

Another object of the invention is to provide a simply constructed device of this character which may be erected in any 25 desired position to apply strain to various objects or devices from any desired point or location.

With these and other objects in view the invention consists in certain novel features 30 of construction as hereinafter shown and described and then specifically pointed out in the claims, and in the drawings illustrative of the preferred embodiment of the invention.

35 Figure 1 is a side elevation of the improved device arranged to apply strain to the strand wires of a fence. Fig. 2 is a side elevation partly in section of the parts shown in Fig. 1. Fig. 3 is a detail view of the forward 40 portion of the main frame. Fig. 4 is a detail view of the rear portion of the main frame. Fig. 5 is a plan view illustrating a slight modification in the construction. Fig. 6 is a view illustrating the use of the device

45 for drawing an automobile from a soft place in the roadway. Fig. 7 is a detached perspective view of the brace employed when the device is applied as in Fig. 6. Fig. 8 is a detached perspective view of the holding 50 member employed when the device is applied as in Fig. 6. Fig. 9 is an enlarged view of a post engaging hook which may be employed with the improved device.

Corresponding and like parts are referred 55 to in the following description and indicated

in all the views of the drawings by the same reference characters.

The improved device comprises a main base frame preferably formed with a curved terminal 10 and side members 11—12 diverging from the curved end and with a transverse intermediate member or brace 13. The terminals of the side members 11—12 are pointed, as shown, to enable them to form seats for themselves in the object against 60 which the device is supported, as for instance a fence post 14. The curved terminal 10 is provided with a seat or pocket 15, while the brace member 13 is provided with a similar pocket or socket 16. The curved 65 terminal 10 and the transverse member 13 are coupled by a longitudinal web 17. Extending beyond the curved terminal 10 is a projection 18 having a central notch 19, the projection and its notch operating to receive 70 the links of a chain, as hereafter explained.

The frame thus far described is preferably formed from a single casting of malleable iron, steel or the like, and will be preferably constructed X-shaped transversely to 75 secure the maximum of strength with the minimum of weight.

The web 17 is provided with bearing apertures 20—21 while the brace member 13 is provided with bearings 22—23 to receive 80 pawls 24—25, the object of the latter to be hereafter explained.

Seated by its ends in the sockets 15—16 is a combined guard and supporting member 26, the ends of the member 26 engaging in 85 the sockets and firmly supported by the side walls of the same. The member 26 is bolted or otherwise secured at 27—28 respectively in the sockets 15—16. By this arrangement the side walls of the sockets firmly support 90 the member 26 from lateral or longitudinal movement and thus relieve the fastening devices 27—28 from shearing strains.

The member 26 is provided with a bearing 95 29 which is located in alinement with the bearing 20, and likewise provided with a bearing 30 which is located in alinement with the bearing 21. The member 26 is preferably formed T-shaped transversely to reduce the weight without decreasing the 100 strength.

The improved device may be arranged to employ a chain or a cable, as may be preferred, for the pulling member, and in Figs. 1 and 2 a chain pulley 31 is shown as the 110

medium for supporting the pulling member, while in Fig. 5 a cable drum 32 is shown in place of the chain wheel 31. The only difference required in the frame to adapt it to either the chain wheel or the drum is to increase the size of the member 26 as illustrated in Fig. 5. The chain wheel 31 or the cable drum 32 is provided at one end with a journal 33 which engages in the bearing 29 of the member 26, and likewise provided with a journal 34 which engages in the bearing 20. The journal 34 is provided with a square or irregular portion 35 upon which a correspondingly shaped bearing 36 of a gear wheel 37 engages. The chain wheel 31, the bearings 33-34 and the irregular shaped portion 35 are all formed in one casting, preferably malleable iron or steel, while the gear 37 together with its bearing 36 is likewise formed in a single casting.

20 The irregular formed portion 35 is preferably slightly tapered, while the bearing 36 is correspondingly tapered so that the gear 37 fits upon the irregular shaped bearing 36 and all looseness thereby prevented. By this arrangement when the member 26 is located in position and the pull member with its journal and irregular portion mounted for rotation therein, the gear 37 will be firmly 25 coupled to the pull member and rotated therewith, and requires no other fastening means to support the parts in position.

25 Mounted for rotation through the bearings 21-30 are the journals 38-39 of a pinion 40, the latter engaging with the gear 37 as shown. The journal 38 is extended and formed square, as shown at 41, while the journal 39 is formed with a similar square extension 42, the extensions designed 30 to receive the operating handle whereby the motion is imparted to the gear 37 and the pull member 31 or 32, as the case may be. The pawls 24-25, as shown in Fig. 1, are designed to engage with the teeth of the gear 37 and thus lock the latter in position. By this arrangement it will be noted that the gears may be rotated in either direction by simply reversing the motion of the operating member upon the terminals 41-42, 35 and by employing the two pawls whatever strain may be secured will be held no matter in which direction the gear 37 may be rotated. By this simple means the improved device is formed reversible in action by simply providing an extra pawl. Of course, it will be understood that one of the pawls remains idle while the other is in use.

40 Formed upon one end of the member 26 is an extension 43 having a relatively large transverse opening 44 and reduced opening 45 connecting with the larger opening, the two openings 44-45 coacting to hold a chain by one of its links. Thus means are provided for anchoring the improved device 45 in position during the pulling action.

When employed as a means for applying strain to the strand wires of a fence the pointed terminals of the base frame will be engaged with the fence post represented at 14 and having a holding or guide chain connected to the other end by utilizing the slotted projection 18-19, as may be preferred, and connecting the guide chain to another post, tree, stake or other object, the latter not being shown as it forms no part 75 of the present invention. A section of chain indicated at 46 having a suitable wire grip represented conventionally at 47 is passed around the chain wheel 31 and engaged by a plurality of its links with the lugs of the 80 wheel, and the pinion 40 rotated by suitable cranks, not shown, applied to one or both of the terminals 41-42, and the pawl 24 or 25, as the case may be, utilized to hold the strain which is thus obtained. If a 85 pull cable or rope is to be employed instead of a chain the construction illustrated in Fig. 5 will be employed.

90 It will be noted that the improved device exclusive of the pawls 24-25 and the fastening devices 27-28, is formed of five parts only, and firmly connected and supported with the pulling strains borne almost entirely by the webs of the sockets 15-16, the fastening devices 27-28 being utilized to hold the member 26 only from lateral strains 95 which are relatively slight.

When the device is to be employed for purposes other than applying strain to strand wires of fences, as for instance in drawing an automobile, as shown in Fig. 6, the frame will be mounted upon the ground and a brace 48 employed to support the frame in inclined position, the brace having a socket 49 to engage the curved portion 100 of the frame. A hook 50 is likewise provided to engage over a portion of the member 26 and connected with a chain or similar device 51 which in turn is supported by an anchor stake 52 driven into the ground at any suitable distance. If required the anchor stake may be replaced by a hook 53 attached to the chain 51 and coupled to a tree, post or a like object. The chain 46 is then coupled to the automobile indicated conventionally at 54 and the latter drawn toward the device by applying rotary power 105 to the pinion as before described.

110 By this simple means the utility of the device is materially increased without change in the construction except to employ the brace 48-49 and the guide chain 51 and its stake 52 or hook 53, as the case may be.

Having thus described the invention, what is claimed as new is:

- 125 1. A device of the class described comprising a supporting frame having spaced bearings and inwardly directed pockets, a combined guard and support engaging at its ends in said pockets and having bearings in 130

alinement with the bearings of said frame, and winding devices supported in said bearings.

2. A device of the class described comprising a supporting frame having spaced bearings and inwardly directed pockets, a combined guard and support engaging at its ends in said pockets and having bearings in alinement with the bearings of said frame, 10 a socket for receiving a guy member, and winding devices supported in said bearings.
3. A device of the class described comprising a supporting frame, a combined guard and support connected at its ends to said 15 frame, a winding device supported by said

frame and support and including a toothed member, means for imparting motion to said toothed member, a brace member having a forked terminal for engaging said device, and an anchor device connected at one end to the device and adapted to be connected at the other end to a stationary support.

In testimony whereof I affix my signature in presence of two witnesses.

JOHN C. B. WOOD. [L. s.]
